(57) **CLAIM**

The ornamental design for a display device set with alternate attachment means, as shown and described.

DESCRIPTION

FIG. 1 is a top view of a display module with its associated clip attachment portion of the display device set with alternate attachment means showing our new design;

FIG. 2 is a side elevation view of the display module shown separately for clarity of illustration;

FIG. 3 is a top perspective view thereof;

FIG. 4 is a top perspective view of the display module with its associated clip attachment means;

FIG. 5 is a top perspective exploded view thereof;

FIG. 6 is a top perspective view of the display module with its associated flexible jacket attachment means;

FIG. 7 is a top perspective exploded view thereof;

FIG. 8 is a top perspective view of the display module with its associated wrist attachment means; and,

FIG. 9 is a top perspective exploded view thereof.

The broken lines are included for the purpose of illustrating portions of the display device set with alternate attachment means that forms no part of the claimed design with no claim made to any particular color scheme.

1 Claim, 9 Drawing Sheets
